CLAIM

The ornamental design for a sensor device, substantially as shown and described.

DESCRIPTION

FIG. 1 shows a perspective view of a design of a sensor device.

FIG. 2 shows a front view of the design.

FIG. 3 shows a rear view of the design.

FIG. 4 shows a left side view of the design.

FIG. 5 shows a right side view of the design.

FIG. 6 shows a top view of the design; and,

FIG. 7 shows a bottom view of the design.

The broken lines shown in the drawings represent unclaimed portions of the sensor device and form no part of the claimed design.
